[57] CLAIM

The ornamental design for a container for ice cream or other products in bulk, substantially as shown.

DESCRIPTION

FIG. 1 is a top plan view of a container for ice cream or other products in bulk showing our new design;

FIG. 2 is a side elevational view;

FIG. 3 is a bottom plan view; and

FIG. 4 is a vertical sectional view taken on the line 4—4 of FIG. 1.

FIG. 3FIG. 4
